(57) **CLAIM**

The ornamental design for an apparatus for reproduction of sound, as shown and described.

DESCRIPTION

Cross reference is made to copending U.S. design patent application Ser. No. 29/627,058 entitled "Apparatus for Reproduction of Sound" by Bell, Andreas, which was filed on even date herewith.

FIG. 1 is a perspective view of an apparatus for reproduction of sound showing my new design;

FIG. 2 is a right side elevational view of the apparatus for reproduction of sound of FIG. 1;

FIG. 3 is a left side elevational view of the apparatus for reproduction of sound of FIG. 1;

FIG. 4 is a front elevational view of the apparatus for reproduction of sound of FIG. 1;

FIG. 5 is a rear elevational view of the apparatus for reproduction of sound of FIG. 1;

FIG. 6 is a top plan view of the apparatus for reproduction of sound of FIG. 1; and,

FIG. 7 is a bottom plan view of the apparatus for reproduction of sound of FIG. 1.

The broken lines shown in the drawings illustrate portions of the apparatus for reproduction of sound that form no part of the claimed design.
